UNITED STATES PATENT OFFICE.

MAX M. SAVLAN, OF PETOSKEY, MICHIGAN.

LACE-RACK.

SPECIFICATION forming part of Letters Patent No. 694,428, dated March 4, 1902.

Application filed August 2, 1901. Serial No. 70,598. (No model.)

To all whom it may concern:

Be it known that I, MAX M. SAVLAN, a citizen of the United States, residing at Petoskey, county of Emmet, State of Michigan, have invented a certain new and useful Improvement 5 in Lace-Racks; and I declare the following to be a full, clear, and exact description of the invention, such as will enable others skilled in the art to which it appertains to make and use 10 the same, reference being had to the accompanying drawings, which form a part of this specification.

My invention has for its object a lace-rack; and it consists of the structure, combination, 15 and arrangement of devices hereinafter described and claimed, and illustrated in the accompanying drawings, in which—

Figure 1 is a view in perspective, showing the rack in position. Fig. 2 is a view in side 20 elevation and in longitudinal section, the same being in folded position. Fig. 3 is a sectional view of the rear portion of applicant's frame on a central line through the adjacent bars *a a* and lengthwise thereof. Fig. 4 is a detail 25 view of a portion of one of the cards. Fig. 5 is a fragmentary view in inverted plan, showing a portion of the frame and the folding support.

My invention more particularly is designed 30 for a lace-rack to display different kinds of laces and in a manner easy of access, so that the goods will be well displayed to the customer and so that the merchant or clerk can readily handle the goods.

While I describe my invention as a lace-rack, I would have it understood that it may be employed for any similar or analogous purpose within the scope of my invention.

I carry out my invention as follows:

In the drawings, A represents a supporting-frame, preferably consisting of side bars *a a*, each provided with end bars *a'*, the end bars preferably having an adjustable engagement 40 the one with the other in any suitable manner. Thus, for instance, one of the end bars may be constructed with an elongated orifice, (indicated at *a²*), through which may be passed a thumb-screw *a³*, engaging the adjacent end bar to hold the two parts of the 45 frame in adjusted position. I do not limit myself solely to making the frames A later-

ally adjustable; but as laces are manufactured of various widths it is sometimes found desirable that the rack should be laterally adjustable, so as to accommodate laces of any 55 width.

Upon the frames A are supported a series of supporting-arms, (indicated at B,) said arms preferably formed of wire bent to form a loop, the upper ends of the loops being turned or flanged outwardly, as shown, said arms thus being constructed to readily receive the cards (indicated at C) upon which the laces are wound, said cards thus being readily removable from the arms B. These arms are 60 secured to each of the side bars *a a*. The cards may be constructed in any suitable manner, but preferably with the body of the card cut away intermediate the corners thereof, leaving the corners projecting, so that the 65 lower corners may readily rest upon the two side bars, while one of the upper corners may bear such marks as may be desired, (indicated, for example, at *b*,) such as the number 70 of the lot, cost, and price.

With one end of the frame A is secured a folding support, (indicated at D,) preferably formed of wire, the extremities having a jointed connection with the frame, as by means of eyes E, engaged with the frame. The extremities of the supporting-arm D are also preferably provided with springs (indicated at F) exerting their tension upon the arm D, the construction being such that the support D may readily be folded underneath the frame 75 A; but when the adjacent end of the frame is lifted the supporting-arm will resume its upright position. The supporting-arm D when in upright position, it will be seen, raises one end of the frame, so that the various cards may rise one above the other step by step, so that the various laces thereupon may readily be seen, as well as the corresponding numbers, price-marks, &c.

These racks may consist of a single frame 80 provided with supporting-arms B and spring-arm D, or a series of them may be connected upon an underlying connecting-bar G at the lower end of the frames. By folding the arm or leg D more ready access may be had to the 85 cards at the adjacent end of the frame.

The portions *b* of the cards are designed

more particularly to bear the lot-number, the cost, and the selling price, while the cards will also display the color of the goods.

It will be evident that the folding supporting-arms D being provided with the springs the support will automatically resume its normal position when free to move. To prevent its moving past its normal position, the extremities thereof may be flanged, as shown at 10 f, to strike against the adjacent portion of the frame, and thereby limit the movement of the support.

The connecting-bar G may have a fixed engagement wherever desired and is shown provided with a groove g, the frames being provided with a pin H to engage in said groove. The adjacent end of the frame will thus be secured against longitudinal movement of the frame, so that with one hand the supporting- 15 standard D may be folded. By grooving the connecting-bar G and providing the individual frames with a pin entering said groove it is evident that the plural frames may be laterally adjusted upon the connecting-bar, as 20 may be desired.

It will be evident that the cutting away of the body of the cards to form the shoulders at the corners also serves to hold the lace upon the cards.

What I claim as my invention is—

1. In a lace-rack the combination with a laterally-adjustable frame consisting of side bars each provided with slotted end bars adjustably engaged the one with the other respectively, of thumb-screws to hold the corresponding ends of the frame in adjusted position, and card-supporting arms upon the upper face of said frame. 30

2. In a lace-rack the combination of an inclined supporting-frame consisting of side 40 bars each provided with end bars having an adjustable engagement the one with the other, and a series of card-supporting arms upon the upper face of said frame.

In testimony whereof I sign this specification in the presence of two witnesses.

MAX M. SAVLAN.
